(57) **CLAIM**

An ornamental design for a bottle carrier, as shown and described.

DESCRIPTION

FIG. 1 is a perspective view of a bottle carrier according to my new design.

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top elevation view of the bottle carrier in an opened position;

FIG. 9 is a side elevation view;

FIG. 10 is an opposite side view;

FIG. 11 is a perspective view of a second embodiment of the carrier shown in FIG. 1;

FIG. 12 is a front elevation view thereof;

FIG. 13 is a rear elevation view thereof;

FIG. 14 is a right side elevation view thereof;

FIG. 15 is a left side elevation view thereof;

FIG. 16 is a top plan view thereof;

FIG. 17 is a top plan view in an opened position;

FIG. 18 is a side elevation view thereof; and,

FIG. 19 is an opposite side elevation thereof.

The broken lines showing a clasp and the interior of the carrier are for the purposes of illustrating environment and form no part of the claimed design.
